UNITED STATES PATENT OFFICE.

JAMES S. LOCHHEAD, OF PITTSBURGH, PENNSYLV

BAR-GRINDING MACHINE.

Application filed April 8, 1922. Serial No. 550,595.

To all whom it may concern:

Be it known that I, JAMES S. LOCHHEAD, residing at Pittsburgh, in the county of Allegheny and State of Pennsylvania, a citizen of the United States, have invented or discovered certain new and useful Improvements in Bar-Grinding Machines, of which improvements the following is a specification.

10 My invention relates to machines for grinding the surfaces of steel bars. Economy of operation requires that such grinding be done expeditiously, and I have invented a machine through which a succession 15 of bars may be advanced in continuous passage, and in which each bar as it advances, and in the course of a single passage through, may be fully ground over its entire surface.

20 In the accompanying drawings Fig. I is a view, in horizontal section, on the plane indicated by the line I—I, Fig. II of a grinding machine for steel bars embodying my invention; Fig. II is a view of the same machine in vertical section, on the plane indicated at II—II, Fig. I. Figs. I and II are in some degree diagrammatic. Figs. III and IV illustrate the mounting of the motors by which the grinding disks are driven, 25 and in that respect give actual illustration, in place of the diagrammatic showing of Figs. I and II, but otherwise Figs. III and IV are views in transverse vertical section, on planes indicated by the lines III—III 30 and IV—IV, Figs. II and I, respectively. Fig. V is a view corresponding to Fig. I, and illustrating an adaptation of the machine to a particular service. Figs. VI and VII are views corresponding to Figs. I and 35 II, and illustrating permissible variations in arrangement.

Referring first to Figs. I and II, means are provided for impelling a steel bar of polygonal cross section with opposite parallel faces (in this instance a rectangular bar B) along a predetermined pathway. These means consist of a pair of pinch rolls 1, 1, and a tension device 2. These two means are remote one from another, and a bar impelled by them, first by the rolls 1, then by both the rolls and the tension device 2, and ultimately by the tension device alone, will be carried across the intervening interval, where it is exposed to the grinding instrumentalities. An arrow indi-

cates the direction of bar advance. The pinch rolls require no detailed explanation. The tension device or puller consists essentially of a screw or screws 3 (a pair of them is shown, extensible and retractable in a base or standard 4, with means of extension and retraction, found in a motor 5, said screws carrying a yoke 6 armed with bar-engaging jaws 7. In this instance it will be seen that the bar-engaging jaws are essentially cam disks which, freely turning, engage the bar frictionally from opposite sides, the security of the grip being increased by traction strain.

It will be understood from what has been said that a bar longer than the interval between pinch rolls and tension device may be introduced between and initially impelled by pinch rolls 1, and presently, engaged by the tension device 2, may be carried forward by both means of impulsion acting together, and ultimately carried through the last portion of its pathway of advance by tension device 2 alone. Supplementary pinch rolls 8, 8 may be stationed adjacent the point where the tension device 2 first engages the work, as shown in Fig. I. It is possible to dispense with the tension device described, and employ merely the two sets of pinch rolls 1, 1 and 8, 8, properly spaced apart, but I prefer to employ the tension device, and to provide the rolls 8 primarily as guiding means, and if desired as supplementary bar-impelling means.

Careful consideration of Figs. I and II of the drawings will make plain the fact that identically such a bar moving structure as is made up of the yoke 6 with its screws 3 and their driving mechanism, may be used as means for pushing the bar from behind, and a pusher so constituted may be combined with pinch rolls or with a tension device, such as that specifically shown, as may be found convenient or desirable.

In the interval between the bar impelling means the pathway of the bar is bordered by the grinding instrumentalities. Each grinding unit is a disk of abrasive material mounted for rotation on its axis, and provided with suitable driving means.

The grinding face of the disk is its flat face. These grinding units are grouped in a plurality of sets, the number of sets corresponding to the shape of the bar: if the bar be rectangular there are two sets; if

hexagonal, three; if octagonal, four, etc. The showing respecting a rectangular bar will suffice, and the general statement may be made and will be fully understood, that 5 the sets are so arranged, that the opposite grinding disks of the several sets, placed in proper angular relation, grind pair by pair, the opposite faces of the bar.

Fig. I shows in plan form above the sets 10 of disks and their driving means which in this instance grind the opposite vertically disposed faces of the rectangular bar B travelling through the machine from right to left, and (being, accurately speaking, a 15 section on the plane I—I, Fig. II) indicates also the grinding means for the upper and lower horizontally disposed faces; Fig. II shows in side elevation the disks with their driving means for grinding the upper 20 and lower faces of the bar and, being a view in section on the line II—II, Fig. I, indicates the means for grinding the vertical faces also. Each set of grinding means consists of a plurality of disks 9, with their 25 faces coincident on either side with the limiting planes of the pathway of bar advance. In this case there are ten disks in each set, five on each side. The axes of the disks are perpendicular to the line of bar advance. 30 Each disk is rotated by its own motor 10, and reference to Figs. III and IV will show that disk and motor constitute a unit, adjustable in a carrying base or foundation. Thus the components of the assembly may be 35 accurately adjusted to service conditions.

The particular setting of the successive disks and the quality of the individual disks will be such as to effect complete and finished 40 grinding in one traverse of the bar through the assembly of disks from end to end: ordinarily the disks at the right-hand end of the lines will be coarse grained, those at the left-hand end fine grained; the number will be adequate to effect the necessary progressive 45 grinding. These matters require mere mention, the rest is apparent to those skilled in the art.

In the intervals between roll passes and 50 disks and between successively arranged disks guide plates 13 may be provided, further defining the pathway of bar advance.

This same machine of Figs. I and II intended primarily for grinding rectangular bars, may be adapted for grinding round 55 bars, and the nature and character of the adaptation is sufficiently indicated in Fig. V. Here the gripping jaws 7 of the tension device 2 are shown to be rotatable coaxially with bar B' (in this case a round bar), and 60 rotation may be imparted to the yoke from the same motor 5 which turns the screws 3. If rolls 8 be mere guide rolls, lacking any 65 touching and bar impelling character, they will be mounted in stationary housings and will not revolve on the axis of bar advance.

For adapting this machine to the grinding of round bars one or both sets of disks may be employed; and if both, the opposite disks of the two sets will be spaced not at different intervals, as for the rectangular bar B, of equal length and breadth, but at equal intervals.

Figs. I and II show the disks of each set arranged in opposite pairs. This is a good, but not a necessary arrangement; Figs. VI and VII show them variously arranged. Figs. I and II show the two sets of disks arranged in interlocked sequence, a pair of one set followed by a pair of the second set, and then a pair of the first set succeeding. This too is a matter which admits of variation. Figs. VI and VII show the two sets arranged to act in sequence, one beginning after the other has finished. Figs. I and II show an arrangement for carrying through a rectangular bar without any turning, and to this end one set of disks is arranged in one general plane and the other in another general plane, at right angles to the first. Figs. VI and VII show the successively acting sets disposed in one and the same general plane, with provision (not shown) for turning the bar through a 90° swing after it has passed through one set of disks and before it enters the second set. Such an arrangement necessitates separation of the two sets at an interval greater than the length of the bar to be ground. And in Figs. VI and VII the zig-zag line α indicates this hiatus, and the place where the bar under grinding is turned.

In the modified machine of Figs. VI and VII the tension device of Figs. I—III is not employed, but instead cooperating sets of pinch rolls 1 and 8, a pair at each end of each set of disks.

Operation involves, first, the proper setting and adjustment of the several grinding disks (and it will be observed from Figs. III and IV that adjustment may by means of screws 11 and 12 be made while operation is in progress). The bars to be ground are advanced from right to left along the pathway indicated. They are engaged initially by the pinch rolls 1 and in due course by the coordinated bar impelling means, whether rolls 8 or tension device 2 or both, and by such means the bars are carried in succession in continuous progress through the machine. While the forward end of a newly entering bar is advancing from pinch rolls 1 through the pathway between the disks, the tension device may be advancing to meet it, from retracted position to the position shown in Figs. I and II, where meeting the newly advancing bar its direction of traverse is reversed and its jaws automatically engage the bar. As the bar so impelled advances, it is ground from end to end and on every side and completely, by the

disks 9. And the whole grinding operation is performed in a single traverse through the machine.

I claim as my invention:

- 5 In a machine for grinding in a single traverse the surfaces of steel bars as they advance uninterruptedly through the machine, the combination of a plurality of grinding disks arranged with their flat grinding faces extending in the opposite bounding planes of the pathway of bar advance, the said discs being rotatable on axes perpendicular to the line of bar advance, a pair of feeding rolls arranged on the intake side of 15 the assembly of disks and adapted to engage a bar on opposite sides and impel it from behind along the pathway between said disks, and a tension device including bar-gripping jaws and a rotatable stem screw-threaded in a stationary block arranged on the delivery 20 side of the assembly of disks and adapted to engage a bar and draw it from ahead along said pathway.

In testimony whereof I have hereunto set my hand.

JAMES S. LOCHHEAD,

Witnesses.
